[57] CLAIM

The ornamental design for a clarinet ligature, substantially as shown and described.

DESCRIPTION

FIG. 1 is a top plan view of a first embodiment the clarinet ligature, showing my new design.

FIG. 2 is a front elevational view thereof, the rear being substantially identical thereto.

FIG. 3 is a sectional view as taken on line III—III of FIG. 2 to more clearly show the design.

FIG. 4 is a bottom plan view thereof.

FIG. 5 is a left end elevational view thereof.

FIG. 6 is a right end elevational view thereof.

FIG. 7 is a top plan view of a second embodiment of the clarinet ligature, showing my new design.

FIG. 8 is a front elevational view thereof the rear being substantially identical thereto.

FIG. 9 is a sectional view as taken on line IX—IX of FIG. 8 to more clearly show the design.

FIG. 10 is a bottom plan view thereof.

FIG. 11 is a left end elevational view thereof.

FIG. 12 is a right end elevational view thereof.
